UNITED STATES PATENT OFFICE

HOWARD S. THORPE, OF YONKERS, NEW YORK

ENGINE

Application filed May 23, 1926. Serial No. 112,281.

This invention consists of improvements in engines, particularly in internal combustion engines of the type shown and described in Letters Patent No. 1,584,567 granted to the 5 applicant May 11th, 1926.

The improvements consist in constructing the engine so that the "piston bodies" or "body members" form the side walls of a single closed annular chamber, the partitions or 10 "cylinder heads" being omitted, and the pistons on one piston body, working opposed to the pistons on the other piston body.

The pistons working opposed in the same chamber, the vibration of the engine is greatly 15 lessened.

The pistons being double acting, and the partitions or "cylinder heads" being omitted, the entire chamber is devoted to the drawing in, compression, combustion and expulsion of 20 the fuel charges, giving the most compact arrangement of "cylinders" possible.

The construction of the piston bodies and their bearings is such that the pressure of the gases between the piston bodies is utilized 25 to prevent the escape of the gases from the chamber until released by the exhaust valves.

Other improvements consist in omitting the "shaft yoke" and having each "piston yoke" act directly on its own crank, the two cranks 30 being spaced 180 degrees apart, so that when the explosion between any two pistons occurs, one crank is on a dead center but the other is approximately 40 degrees to 60 degrees beyond its dead center.

This arrangement of cranks acted on by 35 oscillating yokes results in the opposed pistons being held stationary relatively to each other in their furthermost apart positions and in their closest together positions during this 40 same crank angle of revolution, thus giving opportunity for a more complete fuel charge and for a more complete expulsion of the exhaust gases.

Another advantage of this type of engine 45 not mentioned in the former application is that a long stroke of the piston is obtained with its consequent large fuel charge while the stroke of the crankshaft can be made practically as short as desired, thus permitting a 50 very stiff crankshaft.

Referring to the drawings:

Fig. 1 is an elevation of the flywheel end of the engine with the flywheel removed.

Fig. 2 is a side elevation of the engine.

Fig. 3 is an elevation of the other end of 55 the engine.

Fig. 4 is a diagram showing the relative movements of the cranks and pistons.

Fig. 5 is a perspective view of the two piston bodies with one of the yokes and cranks. 60

Fig. 6 is a longitudinal vertical section through the center of the engine.

Fig. 7 is a section taken substantially on the line 7—7 of Fig. 6 looking in the direction indicated by the arrows.

Fig. 8 is a section taken substantially on the line 8—8 of Fig. 6, looking in the direction indicated by the arrows.

Fig. 9 is a partial horizontal section taken through the axis of the cam shaft.

Fig. 10 is a partial section taken on the line 10—10 of Fig. 7.

Fig. 11 is a partial section taken on the line 11—11 of Fig. 7.

Fig. 12 is a partial section taken on the line 75 12—12 of Fig. 11.

Fig. 13 is a partial section taken on the line 13—13 of Fig. 10.

Fig. 14 is a large scale partial drawing of 80 a valve stem, showing arrangement of guide cap and packing.

Fig. 15 is a large scale drawing of a section through a piston.

Fig. 16 is a large scale drawing of a section taken on the line 16—16 of Fig. 15.

Fig. 17 is a large scale plan view of a piston.

Fig. 18 is a large scale drawing of a modification of the corner construction shown in Fig. 15.

Like reference characters denote like parts 90 throughout the drawings.

Referring to Figs. 2 and 8, the outer engine casing 1 is a cylinder forming the outer wall of an annular chamber 2, the inner wall of the annular chamber being formed by the 95 cylindrical shaped inner casing 3. The two sides of the annular chamber 2 are formed and closed by the flat ring shaped faces 4 of the piston bodies 5 and 6 (Fig. 5).

The piston body 5 has two pistons α formed 100

on its face 4 diametrically opposite and extending across the annular chamber 2 (Figs. 2 and 5). Likewise the piston body 6 has two similar pistons 7 extending across the annular chamber 2.

The back of each piston body, opposite to its face 4, is formed with flanges 9 which form bearing surfaces, the inner parts 14 of the flanges 9 forming acute angles with the faces 4 (Fig. 15). The inner parts 14 of the flanges 9 have shoulders 15 formed on them for a purpose which will be described later.

The flanges 9 and their inner parts 14 are accurately machined to fit and work in bearings 17 and 18 which extend circumferentially around the engine; the bearings 17 having large cylindrical flanges 19 formed on them, each flange 19 having cross straps 20 and 81 extending across its end to which the end cover plates 21 are fastened with machine screws 116. The flanges 19 also have lugs 118 formed on them with holes 129 for bolting the engines to a foundation.

The bearings 18 are joined to their corresponding bearings 17 by webs 22 (Figs. 7 and 15). The bearings 17 also have a flange 23 formed on them by means of which they are fastened to the casing 1 by cap screws 24, a cork or other suitable gasket 25 being compressed between them to make the joint oil tight.

The bearings 18 likewise have a flange 26 formed on them by means of which they are fastened to the inner casing 3 by countersunk head machine screws 27, the screws being kept from loosening by drilling a small hole at each end of the screw slot 28 into the flange 26 and inserting a small piece of spring wire 29 (Fig. 15).

The bearings 17 and 18 each have a shoulder 30 formed on them which with the shoulders 15 form pockets 31 which extend completely around the piston bodies 5 and 6.

The inner parts 14 of the flanges 9 wear themselves into a perfect fit in the bearings 17 and 18 and the pressure of the gases between the faces 4 of the two piston bodies 5 and 6 prevent leakage of the gases past the piston bodies.

Leakage of the gases past the pistons is prevented by straight packing strips 32 and angular packing strips 33 (Figs. 15, 16 and 17), the latter at the outer corners of the piston. The packing strips are pressed into the corners and against the walls of the annular chamber 2 by springs 34 as shown in Fig. 15. The packing strips are prevented from flying out of the pistons when removing the piston bodies by pins 35 passing across the piston through elongated holes 36 in the packing strips.

In Fig. 18 is shown a modification in the construction of the flanges 14 and the bearings 17. As shown in Fig. 18 the positions of the shoulders 15 on the flanges 14 and the

shoulders 30 on the bearings 17 are interchanged and instead of acute angled corners at the edges of the faces 4, short square corners are used, any minute spaces occurring between the short surfaces 69 and the corresponding bearing surfaces being taken up by carbon deposits and sealing them against escape of the gases past the pistons.

Extending diametrically across the back of each piston body is a yoke 37 fitting between lugs 38 formed on the flanges 9 and fastened thereto by countersunk head machine screws 39. (Figs. 5, 6 and 7.) The lower parts of each yoke have slots 40 machined in them in which work a Clayton's sliding journal box consisting of two tapered Babbitt blocks 41 fitting around each crank pin 42, and two tapered gibs 43 which slide in the slots 40 and which can be adjusted to take up wear by means of the studs 44 which are screwed and pinned into the blocks 41 passing through flanges 45 on the gibs 43 to take the nuts 46. The nuts 46 are locked by cotter pins 47.

The crankpins 42 and counterbalance weights 48 form part of the crankshaft 49 extending longitudinally through the center plane of the engine below the axis of the piston bodies. The crankshaft is journalled in the center bearing 50 carried on webs 51 formed on the inner casing 3 and in the bearings 52 formed at each end of the engine on the cross straps 20. Each bearing 52 is fitted with packing 53 in the stuffing box 54 locked by the nut 55. (Fig. 6.)

A gear 56 is keyed to the crankshaft 49 by the key 57 and meshes with a gear 58 which turns the gears 59 of an oil pump. The gear 56 also meshes with the gear 60 of double its diameter pinned to the camshaft 61 by the pin 62.

The gear 60 turns the gear 63 by means of the intermediate gear 64. The gear 63 is pinned to the magneto shaft 65 by the pin 66. The magneto (not shown) can be fastened to the bracket 67 which is bolted to the strap 20 by machine bolts 68.

The cam shaft 61 is journalled coaxial with the piston bodies in a center bearing 70 carried on webs 119 extending across the inner casing 3, and in the bearings 71 at each end of the engine formed at the junction of the cross straps 20 and 81. An exhaust valve cam 72 and an inlet valve cam 73 are pinned to the cam shaft 61 by pins 74 at opposite ends of the center bearing 70.

As shown in Figs. 8 and 10, four spark plugs 75 are screwed into the outer casing 1, midway between the horizontal and vertical planes passing through the axis of the piston bodies.

Opposite each spark plug and seated in the inner casing 3 are two inlet valves 76 and two exhaust valves 77. (Figs. 7, 8 and 13.)

Each pair of inlet valves 76 admit gas from an inlet manifold 78, there being two inlet

manifolds 78 formed on the inner side of the inner casing 3, each manifold supplying two pairs of inlet valves. A pipe 79 screwed into each manifold 78 (Fig. 9) passes through a packing ring 80 in the cross strap 81 and is joined to the cross pipe 82 by the flanged union 83. The cross pipe 82 is fitted with a flange 84 to which is bolted a carburetor (not shown).

In like manner each pair of exhaust valves 77 admit exhaust gases to an exhaust manifold 85, there being two exhaust manifolds formed on the inner side of the inner casing 3 parallel to the inlet manifolds, each exhaust manifold taking exhaust gases from two pairs of exhaust valves. A pipe 86 (Fig. 7), screwed into each manifold 85, passes through a packing ring 87 (Fig. 2) in the cross strap 81 and is joined to a pipe 88 by a flanged union 89. The pipes 88 discharge the exhaust gases to the atmosphere or to a muffler (not shown).

The valve stems 90 pass through guides 91 formed on their manifold, each guide having a metal cap 92 (Fig. 14) fitting over it with suitable packing 93 between the cap and the top of the guide. Each cap 92 has a flange 94 formed on it to form a seat for the valve spring 95. The valve spring keeps the flange 94 seated on the manifold, the packing 93 being of such a thickness, that it becomes compressed and prevents an excess quantity of oil from working down the valve stem.

Each pair of inlet valves and each pair of exhaust valves has a roller cam follower 96 (Fig. 12) rotatably carried on a pin 104 in the valve plunger 97. The valve plunger fits over each valve stem 90 of the pair and carries an adjusting set screw 98 and locknut 99 for each valve stem. The valve plunger 97 also fits and slides over a central guide rod 100 screwed into a socket 101 in the manifold. A third spring 102 placed around the socket and guide rod 100 is acted upon by the valve plunger.

The outer casing 1 has an oil or water jacket space 103 formed in it. Instead of fitting or forming the inner casing 3, the piston bodies and the exhaust manifolds with separate oil or water jackets, I prefer to cool these parts and the outer casing 1 with the lubricating oil as follows:

The oil is pumped from a radiator or other suitable cooling device (not shown) through a pipe 114 fitted with a shut-off valve 115 (Fig. 3), into the lower part of the engine by the oil pump gears 59. The oil rises up through the engine lubricating all the moving parts and cooling the inner casing 3, the pistons, piston bodies and exhaust manifolds. It passes out at the top through the pipe 105 and is carried to the bottom of the outer casing 1 in which it rises and passes out at the top through the pipe 106 to the cooling device.

The two pockets 31 extending around each

piston body 5 and 6 trap any excess of oil working past the piston bodies, the inner and outer pockets 31 in each piston body being connected at the bottom by a drilled hole 107. The pipes 108 screwed into lugs 109 at the bottom of the engine, connect with the bottom of the outer pockets 31 by means of drilled holes 110 and the oil in the pockets drained away to tank or other receptacle (not shown).

The pipes 111 screwed into lugs 112 at the bottom of the engine and fitted with shut off valves 113 permit the drainage of the oil in the engine to the same tank or receptacle when desired. The valve 115 is closed for this operation. When the engine is running the valve 115 is open and the valves 113 closed. The drainage tank or receptacle may be fitted with a hand or small motor pump to transfer the oil to the cooling device.

When the engine is not running, the pressure of the springs in the pistons presses the piston bodies against their bearings preventing flooding of the annular chamber 2, the pockets 31 trapping and draining whatever leakage occurs.

The operation of the engine is as follows, attention being particularly directed to the diagram Fig. 4:

The line EE represents the center line of the yoke attached to piston body 5 which carries the pistons *x*. Likewise the line FF represents the center line of the yoke attached to piston body 6 which carries the pistons *y*.

The crank that the yoke represented by the line EE acts upon is denoted by *Xo* and the other crank by *yo*, the cranks being spaced 180 degrees apart and rotating in the direction indicated by the arrow.

The combustion chambers where the spark plugs are located are denoted by *a*, *b*, *c*, and *d*. The firing order is *a*, *b*, *c*, *d*.

In the diagram the crank *xo* is shown on the left hand dead center, the crank *yo* is at the angle θ beyond the right hand dead center and the pistons *x* and *y* are at the positions shown with the fuel charge ready to be fired at *a*. At the explosion the pistons *x* and *y* move apart at *a* and *c* and approach each other towards *b* and *d*, compressing a fuel charge at *b*, drawing in a fuel charge at *c* and exhausting at *d*.

When the crank *xo* has moved to its other dead center *x'o*, the yoke represented by the line EE has moved to the position denoted by the dashed line E'E' and the pistons *x* have moved to the positions *x*₁. At the same time the crank *yo* has moved to the position *y'o*, the yoke represented by the line FF has moved to the position denoted by the dashed line F'F' and the pistons *y* to the positions *y*.

As the cranks now move through the angle θ , the pistons *x* and *y* move together in the same direction without changing their distance apart, the *x* pistons moving from positions *x*₁ to *x*₂ and the *y* pistons moving from

positions y_1 to y_2 . The crank y is now at the left hand dead center and the crank x is at the angle θ beyond the right hand center, the cranks having moved through one half 5 a revolution and the fuel charge is ready to be fired at b .

As the crank y now moves to the right hand dead center, the crank x moves through the same angle. The pistons x 10 move to positions denoted by x_3 and the pistons y to the positions denoted by y_3 . As the cranks now move through the angle θ the x pistons and y pistons move together again to the positions originally 15 started with, the cranks having made a complete revolution and the fuel charge is ready to be fired at C .

The movements of the x pistons from the explosion at a to the explosion at b are denoted by arc arrows m , and their movements 20 from the explosion at b to the explosion at c by the arc arrows m' . Likewise the movements of the y pistons from the explosion at a to the explosion at b are denoted by the arc 25 arrows r , and their movements from the explosion at b to the explosion at c by the arc arrows r' .

From the foregoing it will be seen that the 30 explosions occur at regular intervals and for the unit engine described and illustrated, the explosions occur the same as for a conventional four cylinder, 4 cycle, engine.

As one of the cranks is at an appreciable angle beyond the dead center whenever the 35 fuel charge is fired, a much more effective turning effort is applied to the shaft.

The pistons working opposed to each other 40 in the same plane and all the moving parts being easily balanced, the vibration is greatly lessened.

The pistons holding their relative furthest apart and nearest together positions while the cranks move through the angle θ give opportunity for drawing in a more 45 complete fuel charge and for a more complete expulsion of the exhaust gases.

The momentum of the piston bodies acts 50 in opposite directions and is cushioned and absorbed at every stroke by the compression occurring in one of the combustion chambers.

In Fig. 8 the directions of rotation of 55 crankshaft and camshaft are denoted by arrows; the a chamber has been fired, b is compressing, c is taking in fuel charge, and d is exhausting.

Although an internal combustion engine 60 has been particularly described, it will be understood that the engine may be made to operate on any other fluid such as steam. Furthermore as an internal combustion engine the engine may be constructed to operate 65 on the two cycle principle.

In conclusion, therefore, although certain 70 specific embodiments of the invention have been particularly shown and described, I do

not intend to limit myself to this exact structure but wish it understood that further changes in the construction and the arrangements of the various cooperating parts may be made without departing from the spirit 75 or scope of the invention as expressed in the following claims.

What I claim and desire to secure by Letters Patent is:

1. In an engine, a closed annular cylinder 75 having oscillatable side walls carrying opposed pistons, the said walls having acute angle flanges formed on their outside faces to form bearing surfaces supported and oscillating in similarly shaped bearing members. 80

2. In an engine, a closed annular cylinder having oscillatable side walls carrying opposed pistons, the said walls having acute angle flanges formed on their outside faces 85 to form bearing surfaces supported and oscillating in similarly shaped bearing members and having oil traps or pockets between said flanges and their corresponding bearing surfaces. 90

3. In an engine, a closed annular cylinder having oscillatable side walls carrying opposed pistons, the side walls having bevelled bearing surfaces formed on their outside faces to turn in similarly shaped bearing members, 95 the contact between each said bevelled bearing surface and its corresponding bearing member being interrupted by a pocket or oil trap extending circumferentially round said bearing surface and its corresponding bearing member and means for draining said pockets or oil traps. 100

4. In an engine, a crankshaft, a closed annular cylinder disposed around said shaft and opposed oscillatable pistons therein operatively connected to said shaft, and inlet and exhaust poppet valves opening into said annular chamber between the opposed pistons, the said valves being seated in the inner wall of said annular cylinder and actuated by cams carried on a cam shaft coaxial with the annular chamber and operatively connected with said crankshaft. 110

5. In an engine, a crankshaft, a closed annular chamber disposed around said shaft, 115 the side walls of the annular chamber oscillatable but non-rotating and carrying pistons, the said side walls each carrying a yoke operatively connected to a crank on said crankshaft. 120

6. In an engine, a crankshaft, a closed annular chamber disposed around said shaft, the side walls of the annular chamber oscillatable but non-rotating and carrying pistons extending across said annular chamber, 125 the pistons on one wall working opposed to the pistons on the other wall, the said side walls each carrying a yoke operatively connected to a crank on said crankshaft.

7. In an engine, a crankshaft, a closed an-

nular chamber disposed around said shaft, the side walls of the annular chamber oscillatable but non-rotating and carrying opposed pistons and said walls each carrying a yoke operatively connected to a crank on said crankshaft said cranks being spaced 180 degrees apart.

8. In an engine, a closed annular chamber undivided by partitions and opposed oscillatable non-rotating pistons therein, one set of pistons carried by a member that forms one side wall of the annular chamber, and the opposed set of pistons carried by a member that forms the other side wall of the annular chamber.

9. In an engine, a crankshaft, a closed annular chamber disposed around said shaft, the side walls of the annular chamber oscillatable but non-rotating and carrying pistons operatively connected to said crankshaft.

10. In an engine, a crankshaft, a closed annular chamber disposed around said shaft, the side walls of the annular chamber oscillatable but non-rotating carrying pistons operatively connected to said crankshaft, the said pistons on one wall working opposed to the pistons on the other wall and packing members between said pistons and annular chamber walls.

11. In an engine, a closed annular chamber undivided by partitions, the side walls of said annular chamber oscillatable but non-rotating and carrying pistons operating in said annular chamber, said pistons being hollow and open to the crankcase and cooled by the lubricating oil filling and flowing through the crankcase.

12. In an engine, a crankcase, an annular chamber with pistons working in it, said pistons being hollow and open to said crankcase and cooled by the lubricating oil filling and flowing through the crankcase, and means for trapping and draining off the oil working past the pistons.

13. In witness whereof, I have hereunto set my hand this 26th day of May, 1926.

HOWARD S. THORPE.
